UNITED STATES PATENT OFFICE.

FIDEL SANCHEZ, OF GUADALAJARA, MEXICO; JOSE SANCHEZ G. ADMINISTRATOR OF
SAID FIDEL SANCHEZ, DECEASED.

CLOSING DEVICE AND SAFETY SEAL.

Application filed January 30, 1925, Serial No. 5,831, and in Mexico December 30, 1924.

My invention refers to a new and useful seal or unbreakable and safety seal, or more particularly to means for insuring the safe closing of railroad freight cars, baggage 5 cars, money bags, refrigerating cars, water meters or electric meters, and in general every place where a safety seal is desired, as once this seal is closed it can not be opened again without destroying or cutting the ribbon or strap attached to the seal.

Such results are obtained by means of the mechanism illustrated in the drawings here-with attached, reference to which is made as follows:

15 Fig. 1 is a perspective view, partly broken away, of the seal prior to the assembling thereof.

Fig. 2 is a longitudinal sectional view showing the complete device as applied to 20 use.

Fig. 3 is a perspective view of the complete seal.

Fig. 4 is a partial perspective view of the internal mechanism of the seal removed.

25 Fig. 5 is a perspective view of the sliding piece of the internal mechanism of the parts.

Fig. 6 is a detail of the split rings forming part of the device, one of which is shown in section.

30 Fig. 7 is a perspective view of a further part of the internal mechanism of the seal.

Similar reference numbers make reference to the same parts or pieces in the different figures.

35 The container or case of the seal (Fig. 1) is formed by the cup 11, which can either have a cylindrical form or any other desired shape that can be stamped. That is formed by one piece provided with a slot 12 in its 40 curved face, for the admission of the extremity of ribbon or handle, another slot 13 in its bottom for the passage of the handle and a flange 14 disposed in the upper section of the cup, perpendicular to its base, which can be 45 used as a lead for the internal mechanism, to maintain and place the same in position; said cup being provided in its upper edge with two flange sections 15 to join the cover on the cup. This cover 16 is slightly curved and is

50 attached in part to the cup, which is bent to cover the same, after which the cover 16 is attached in a point diametrically opposed by means of the buckle 17, provided with the slot 18, which slot coincides with the slot 12 on 55 the cup, and said buckle attached by means

of the ribbon or strap 19, constitutes the handle of the seal, said strap being provided with a perforation 20 in one of its extremities for the purpose of anchoring this end of the handle in the closing mechanism by means 60 of the hoops or rings that are hooked in said perforation thus effecting the closing operation. The different parts of the cup, cover, buckle and handle constitute one single piece in itself, of any metallic material or any 65 other suitable for the purpose.

The interior mechanism is lodged in the inside of the cup 1, and constitutes four pieces; one crown or pedestal 21, (Fig. 7) formed by a flattened tubular section or a 70 double section, of the form and structure shown in the drawing, provided with angular grooves 22, the horizontal end of the groove being the one that serves as slidable 75 groove for the hoops or rings, and the interior sides, which constitute the guides of the said rings; the said part being of a wider opening in its inferior part and in its superior part leaving just a space sufficiently wide for the sliding of the piece that will be 80 later described. In its lower end and in the centre it is formed with a semi-circular cut 23, which cut engages the flange 14 on the cup thus keeping the mechanism in position.

The slidable piece 24 (Fig. 5) is formed 85 with double walls joined along their lower part with folded portions 25 at right angle for the sake of safety and resistance, and provided with a hole in its centre as at 26. This piece 24 is inserted in the crown or pedestal 90 21, and receives the end of the strap or handle 19 that is introduced in the interior of said piece 24 between its walls. The hole 26 coincides with the perforation 20 of the ribbon 95 when introducing the end of the handle or strap in the slidable piece 24. Two hoops or rings 27, opened at one point are disposed in the slots 22 of the pedestal 21, introducing 100 said rings through the horizontal end of the slots, one on each side, and keeping the same in position on the other ends of the said slots, which constitute the guide of the rings. The extremities of each of the rings are set 105 on the plate of the slidable piece 24, underneath the perforation, in such a way that when pushing the piece 24, through the action of the end of the strap or handle 19, said perforation 20 coincides with the perforation 26, the ends of the rings close within the 110 perforations, thus effecting the closing of the

handle through the action of the rings, which are thus joined in the perforations of the handle 19 and slidable piece 24. The closing mechanism thus formed by the four pieces 5 consisting of: pedestal or crown 21, (Fig. 7); slidable piece 24, (Fig. 5) and the two rings 27 (Fig. 6) the mechanism of which is disposed in the interior of the cup 11, the same being set in the manner represented in 10 Fig. 4, and in the cross section on Fig. 2. The cover 16 is bent over the cup or case 11, covering its entrance and is fixed by means of the flanges 15, which fasten over the cover. The buckle 17, is also folded in the interior of 15 the cup, thus forming a double wall and coinciding the groove 18 with the groove 12 on the cup, for which purpose the strap or handle 19 that should preferably be of a flexible material will go through the lower groove 20 13 on the base of the cup, such as described in Fig. 2, and when out of the same will form a free handle to be inserted in the place to be shut. Once in place the end will be introduced through the groove 12 of the cup to 25 go into the internal mechanism, thus fixing the cover when passing through the groove of the buckle 17 and holding the end of the strap through the hole 20, by means of the rings in the mechanism, such as described 30 heretofore, such closing once shut not being separable, except by destruction of the handle on the same, thereby obtaining an absolutely safe seal.

Having thus described my invention, what 35 I claim as my invention and I therefore desire to protect by patent is the following:

1. In a safety seal, a container having slots 40 therein and an open side, a cover carried by the container and adapted to be folded over the open side of the latter, a strap carried by the cover and having a slot therein adapted, when the cover is closed and the strap is passed through one of the slots in the container, to register with the other slot in the 45 container to permit the insertion of the free end of the strap through said registering slots whereby to lock the cover in closed position, and means arranged within the container and coacting with the extremity of the strap for 50 fastening the latter in place.

2. In a safety seal, a container having an open side and a slot therein, a cover carried by the container adapted to be folded over the open side thereof, a strap carried by the cover 55 adapted to be passed through the slot in the container whereby a portion of the strap is received within the container, the portion of the strap being located within the container and the contiguous portion of the latter having slots therein to receive the outer extremity of the strap, and means located in the container for fastening the strap in position.

3. In a safety seal, a container having a slot 65 therein, a strap carried by the container and having the extremity thereof apertured and adapted for insertion in said slot, and means coacting with the inserted end of the strap for preventing withdrawal of the latter from the container, the last mentioned means including a slide having the ends turned outwardly to guide the movement of the slide in the container, a guide for said slide having the ends bent angularly to position the same within the container, and locking split rings 70 associated with the slide and guide and adapted to coact with the apertured end of the strap to prevent withdrawal of the latter. 75

4. In a safety seal, a container having a slot 80 therein, a strap carried by the container and having the extremity thereof apertured and adapted for insertion in said slot, and means coacting with the inserted end of the strap for preventing withdrawal of the latter from the container, the last mentioned means including a slide having the ends turned outwardly to guide the movement of the slide in the container, a guide for said slide having the ends bent angularly to position the same within the container, and locking split rings 85 associated with the slide and guide and adapted to coact with the apertured end of the strap to prevent withdrawal of the latter, and means for preventing the slide and guide from turning within the container. 90

5. In a safety seal, a container having a 95 slot therein, a strap carried by the container and having the extremity thereof apertured and adapted for insertion in said slot, and means coacting with the inserted end of the strap for preventing withdrawal of the latter from the container, the last mentioned means including a slide having the ends turned outwardly to guide the movement of the slide in the container, a guide for said slide having the ends bent angularly to position the same within the container, and locking split rings 100 associated with the slide and guide and adapted to coact with the apertured end of the strap to prevent withdrawal of the latter, said guide having an individual guiding slot for each ring. 105

6. In a seal, a container, a cover carried by 110 said container adapted to be folded down upon the latter, a strap carried by the cover, and a locking device for fastening the outward extremity of the strap in the container and being separate and removable from the latter, the container and strap having apertures therein adapted to receive the strap and the latter acting upon insertion in the container to prevent opening of the cover. 115

In testimony whereof I affix my signature.

FIDEL SANCHEZ.
